(57) CLAIM

The ornamental design for a skirt, as shown and described.

DESCRIPTION

FIG. 1 is a front view of the skirt, showing my new design; FIG. 2 is a back view thereof;

FIG. 3 is a right side view thereof; and,

FIG. 4 is a left side view thereof.

The broken lines illustrate portions of the skirt and form no part of the claimed design.

1 Claim, 4 Drawing Sheets

FIG. 1

FIG. 2

FIG. 4
